Primary Examiner — Robert M Spear*Assistant Examiner* — Ryan Harvey(74) *Attorney, Agent, or Firm* — Stephen C. Beuerle; Procopio Cory Hargreaves & Savitch LLP(57) **CLAIM**

The ornamental design for a jumping exercise device, as shown and described.

DESCRIPTION

FIG. 1 is a perspective view of the jumping exercise device; FIG. 2 is a front elevation view of the jumping exercise device;

FIG. 3 is a rear elevation view of the jumping exercise device; FIG. 4 is a left side elevational view of the jumping exercise device;

FIG. 5 is a right side elevational view of the jumping exercise device;

FIG. 6 is a top plan view of the jumping exercise device; and, FIG. 7 is a bottom plan view of the exercise device.
